CLAIM

The ornamental design for a bridging clip with a rib, as shown and described.

DESCRIPTION

FIG. 1 is a top perspective view of a bridging clip with a rib, showing our new design;

FIG. 2 is a bottom perspective view of the bridging clip with a rib of FIG. 1;

FIG. 3 is a front elevational view of the bridging clip with a rib of FIG. 1, the rear elevational view being a mirror image thereof;

FIG. 4 is a left elevational view of the bridging clip with a rib of FIG. 1;

FIG. 5 is a right elevational view of the bridging clip with a rib of FIG. 1;

FIG. 6 is a top plan view of the bridging clip with a rib of FIG. 1;

FIG. 7 is a bottom plan view of the bridging clip with a rib of FIG. 1; and,

FIG. 8 is a top perspective view of the bridging clip with a rib of FIG. 1 shown in conjunction with a horizontal bridging member and a vertical stud.

The broken lines shown in the drawings are included for purposes of illustrating portions of the bridging clip with a rib or environmental structure that form no part of the claimed design.
